UNITED STATES PATENT OFFICE.

CHARLES J. SONNEMA, OF PEKIN, ILLINOIS.

LANTERN.

SPECIFICATION forming part of Letters Patent No. 658,873, dated October 2, 1900.

Application filed January 23, 1900 Serial No. 2,551. (No model.)

To all whom it may concern.

Be it known that I, CHARLES J. SONNEMA, a citizen of the United States, residing at Pekin, in the county of Tazewell and State of Illinois, have invented certain new and useful Improvements in Lanterns; and I do hereby declare that the following is a full, clear, and exact description of the invention, which will enable others skilled in the art to which it appertains to make and use the same.

This invention relates to improvements in lanterns of that class used on buggies, delivery-wagons, and the like.

One object of my invention is to utilize all the light given by the lantern. I accomplish this by a peculiar arrangement of reflectors, which will be hereinafter more fully described.

A further object is to arrange the lantern so that light may be thrown at either side of the road or at both sides simultaneously, as desired.

A still further object is to arrange a lantern so that it may be hung at the side of the vehicle, on the dashboard, or beneath such vehicle.

In the appended drawings, Figure 1 is a front elevation of the lantern with a reflector attached thereto. Fig. 2 is a plan view of the same. Fig. 3 is a perspective view of the means for locking a hinged reflector. Fig. 4 is a perspective view of the entire reflector detached from the lantern. Fig. 5 is a perspective view of the tubular portion of the lantern, showing a hanger designed for use on the bottom of the vehicle when the lantern is to be carried beneath it. Fig. 6 is a side view of the body of a vehicle, showing the lantern hung therefrom. Fig. 7 is a plan view of a portion of the vehicle-body, showing my improved lantern hung at the side and one on the dashboard to show the manner of carrying.

In the figures, A indicates the limbs or tubes of the lantern, which ordinarily converge toward the top, as shown in Fig. 1. The lantern itself is of the ordinary form, and I attach no claim to the construction thereof; but with my reflector any of the lanterns now in common use may be employed, the reflector being so constructed that any lantern of the tubular class may be used. The construction of the reflector may be understood from Fig.

4, in which B indicates the back, which may be made of sheet metal, nickelized or otherwise protected against rusting, and which will furnish a bright reflecting-surface. The bottom and top, respectively, project forward substantially parallel with each other and are also reflecting-surfaces. To the back are hinged movable reflectors E and F, having projecting wings E' and F', respectively, for holding the light within the body. The top and bottom portions are cut out, as shown, to fit the curve of the lantern, and to the projection formed thereby are soldered or otherwise secured guides G, which are designed to slip down over the tubes A. To one of the guides is hinged a curved reflector H, which may be opened, as shown by broken lines in Fig. 2 and also in Fig. 4. The top D being cut out, as indicated, fits the curve of the top plate a of the lantern, and the bottom registers with the curve of the oil-fount b, and the curved reflector H, just mentioned, surrounds the front of said plate a. This incloses the lantern entirely at the back and partially at the front, said curved reflector H being utilized to reflect to the ground the rays of light which would otherwise be thrown upward. I may make the reflecting portion F perfectly rigid by forming it with main body; but I show it hinged to the latter and may so use it. The reflecting portion E, I prefer to hinge, as I have shown, although I may make it rigid. Secured to the outside of the back B are two cleats I, which are designed to pass over the dashboard, as shown in Fig. 7. On the outside of the reflector E are two similar cleats J, adapted to be slipped over the side, as shown in said Fig. 7. In carrying the lantern beneath the vehicle I provide a hinged bracket or support, Fig. 5, consisting of a plate K, secured to the bottom of the vehicle by suitable screws and having hinged thereto a portion L, whose wings M are slotted at N. Said wings are created by cutting out a portion of the metal to allow the arrangement to go under the tube A and pass the depending portion c thereof. The slots N are adapted to be held by two screws or similar portions, which may be turned at right angles to the slot, so that said portion L may be held in place. In addition to these, as shown in Fig. 6, a wire O is held, by means of a screw-eye,

in the bottom of the vehicle-body, while the other end is attached in suitable manner to the reflector at P. A hook Q, loosely secured to the bottom of the reflector, engages with an eye R, attached to the oil-fount of the lantern. This keeps the lantern from swinging, the wire O being sufficiently stiff to resist a thrust in the direction of its length. The reflecting portions E and F, whether open or closed, may be locked in suitable manner, one method being used in Figs. 1 and 3, in which E² is a tongue secured to the reflector E and perforated to pass over an eye E³, secured to the tube A of the lantern. A suitable pin or peg passes through an eye and locks the reflector in the closed position. The same means may be used for the reflector F and indicated by F² in Fig. 4, and any suitable device may be used for locking the reflector in its open position. The front reflector H may be locked in any suitable manner, and the means I have shown in Fig. 1 is such that a slight movement thereof will enable the user to withdraw the wire loops H², secured to the said reflector, from eyes H' on the tube A, as will be readily understood. Other arrangements may be employed for securing the lantern to the vehicle in the various positions. The reflector as a whole may be entirely rigid or without any hinged portion except the reflector H. The guides G are cut out at the front to allow them to pass down over the tube A without interfering with the locking device. When placed under the vehicle, the light is thrown ahead for a long distance. The bright surface of the interior of the reflector uses all the light-rays and uses them to advantage. It will be seen that though the lantern is rigidly hung on the vehicle, whether it is beneath or in front, light may be thrown to either side of the road by opening the proper portion E or F. It is evident that the hinged portion E will not be used when the lantern is hung at the side of the vehicle, because that portion will be locked to the guide by the means described. In removing the reflector from the lantern it is only necessary to release the hook Q from the eye R on the oil-fount and then raise the reflector to carry the guides G away from the tube A. This may be done without interfering with the reflector H; but it is not necessary to lock the hook Q except when the lantern is hung beneath the vehicle; but in the latter case the swinging of the lantern away from the wire O would move the reflector from its position, as will be understood.

Having thus described my invention, I claim—

60 1. A reflector for lanterns comprising a box for partially inclosing the lantern, composed of the back B, bottom and top C and D respectively, said bottom and top having curved openings to surround said lantern, guides G

secured to the top and bottom portions and 65 adapted to pass over the tube of the lantern, a reflecting portion H hinged to one of the guides and adapted to be attached to the opposite guide, the hinged sides E and F hinged to the back B and adapted to be opened and 70 closed for the purpose set forth.

2. In a lantern, the combination of the tube A, a reflector comprising a box adapted to partially inclose the lantern and fit snugly around one side thereof to prevent exit of 75 light at that side, said box adapted to be attached to the lantern-tube A, adjustable reflecting sides for the box and means for locking same in any desired position for the purposes set forth. 80

3. In a lantern, the combination of the tubes A of the lantern, a reflector adapted to fit snugly around one side of the lantern; said box adapted to be attached to the said lantern-tube A, adjustable reflecting sides for 85 the box, means for locking same in the position desired, a reflector H hinged to the front of the lantern and adapted to open and close substantially as set forth.

4. In a reflector, the combination of a back 90 B having adjustable sides E and F, upper and lower wings thereof, guides G for attachment to a lantern, cleats I and J on the back and side of such reflector for the purposes set forth and a reflector H on the front all arranged 95 substantially as and for the purpose set forth.

5. In a device of the character described for use on vehicles the lantern-tube A thereof adapted to be attached to a vehicle, a hanger composed of a portion K secured to the bottom of the vehicle, a portion L hinged on the said portion K and adapted to receive the tube A, means for locking the said portion L to support the tube therein, a reflector-box composed of a back B, bottom and top C and D 105 respectively, sides E and F, the guides G and the reflector H all arranged as set forth, and a wire O attached at one end to the bottom of the vehicle and at the other to the reflector, a hook Q attached to the body of the reflector 110 and adapted for attachment to the oil-fount of the lantern, all arranged as set forth.

6. In a lantern for the purposes described, the main reflector partially inclosing the lantern, the sides thereof adapted to be opened 115 and closed, the front reflector H hinged to said reflector at one side and adapted to swing horizontally on its hinge and locked in its closed position in combination with guides on the said body for engaging the lantern-tube 120 and means for locking the main reflector to the lantern substantially as set forth.

In testimony whereof I affix my signature in presence of two witnesses.

CHARLES J. SONNEMA.
